UNITED STATES PATENT OFFICE.

STEPHEN D. FIELD, OF NEW YORK, N. Y.

DYNAMO MULTIPLE TELEGRAPH.

SPECIFICATION forming part of Letters Patent No. 288,786, dated November 20, 1883.

Application filed August 29, 1882. (No model.)

To all whom it may concern:

Be it known that I, STEPHEN D. FIELD, a citizen of the United States, and a resident in the city, county, and State of New York, have 5 invented certain new and useful Improvements in the Method of and Apparatus for Multiple Telegraphy, of which the following is a specification.

My invention relates to the construction and 10 organization of apparatus employed for transmitting several communications telegraphically over a single conductor, in either or both directions, simultaneously.

Heretofore it has been customary, in organizing apparatus for multiple telegraphy, to provide at each station transmitting-keys for sending to the main line currents of different characters, the character of each current being dependent upon the particular key, or combination 15 of keys, which may at any time be employed, and to so include in the circuit of the main line receiving-instruments adapted to respond to the currents coming from the distant station, that each current having traversed any 20 or all of the instruments will reach the earth by way of the transmitting-keys and the battery-connections. To insure the successful operation of the receiving-instruments in response to their respective currents, it is essential that 25 the comparative resistances of the different branch circuits, which the incoming currents are compelled at different times to traverse, be accurately adjusted or equated, and that the balance of the line be at all times correctly 30 maintained. Owing to the several facts that the path by which an incoming current reaches the earth changes in accordance with the relative positions of the respective keys at the receiving-station, that more or less battery- 35 power and consequent resistance is included in the earth-circuit according to these positions, and that the contact-points of the keys forming a portion of the earth-circuit at any given moment offer more or less resistance 40 according as they chance to form poor or good connections, it is found exceedingly difficult to maintain the balance of the line with sufficient accuracy to render such systems practically successful.

45 The object of my invention is to provide means for sending to the line currents or im-

pulses of any required character, and at the same time to provide for the incoming currents a ground-connection of constant resistance, whereby currents from the receiving-instruments may reach the earth independently 55 of the transmitting devices.

My invention consists in placing an armature adapted to be rotated at any required velocity within the field of force of one or more 60 solenoids electrically independent thereof, but capable of being traversed by currents, impulses, or undulations of electricity of determinate strength and polarity, thereby creating a field of magnetic force through or within 65 which the armature moves. Corresponding currents, impulses, or undulations will thereby be generated in the coils of the armature, which currents are transmitted to the line by means of suitable commutators.

70 It also consists in combining with the transmitting apparatus suitable receiving-instruments adapted to respond, respectively, to different classes of currents transmitted from the opposite terminal of the line, and in providing an electrical connection between the receiving-instruments and the earth by way of the commutators of the armature, one of which is arranged to receive currents of one polarity and is connected with the line-wire, while the 75 other is arranged for receiving currents of the opposite polarity and is connected with the earth.

78 There are several methods of applying my invention to multiple telegraphy, all dependent, however, upon the same general principle of generating the currents to be transmitted upon the main line in the coils of an armature in response to and in correspondence with the field of force created by the transmission of electric currents through solenoids 85 located in the vicinity of the armature, and of providing for the incoming currents an earth-connection which is independent of the transmitting devices and circuits.

90 Of the accompanying drawings, illustrating the general method of carrying out my invention, Figure 1 is a diagram showing its application to sextuplex telegraphy, and Figs. 2 and 3 to two different systems of quadruplex 95 telegraphy.

98 Referring to Fig. 1, L represents a main line

uniting two telegraphic stations, which, for convenience, will be hereinafter termed "station I" and "station II." At station I, I have shown three independent keys or transmitting devices, two of which are adapted to send currents of determinate strength and polarity through corresponding local circuits, constituting solenoids about a rotating armature. The remaining key acts to produce rhythmic electrical pulsations or variations in its local circuit or solenoid. At station II, I have shown three receiving-instruments adapted to respond, respectively, to currents of a given strength without reference to their polarity, currents of a given polarity, and rhythmical pulsations. The method of transmitting the currents or impulses of the several classes will be more particularly described with reference to the construction of the apparatus itself. The receiving apparatus R at station I, I have indicated merely, deeming it unnecessary to illustrate it in full, as it is in effect the same as that shown at station II.

Considering first the transmitting apparatus, A represents an armature having the same general characteristics as the armatures commonly employed in dynamo-electric generators. In this instance it is one of the type known as the "Gramme ring," and consisting of coils 25 of insulated wire a , wound upon a soft-iron ring, a' , in a manner well understood. It is constructed to be rotated by means of suitable motor power and connections. (Not shown.) Two commutator-brushes or systems of brushes, 30 b and b' , rest against the surface of the commutator B, which is of the usual construction and revolves with the armature A. The brushes b and b' are so arranged with reference to the commutator-sections that currents of 35 one polarity generated within the coils of the armature will be received upon the brush b and transmitted to the line L, with which it is connected, while currents of the opposite polarity will be received upon the brush b' and 40 reach the earth at E through the wire l. Contrary to the method adopted in dynamo-electric machines, however, no portion of the currents generated in the coils of the armature is employed for intensifying the field of magnetic force; but the latter is entirely dependent upon the passage of currents from three local batteries, o' o^2 o^3 , through the coils of 45 wire constituting three solenoids, c' c^2 c^3 , respectively included in the circuits of the three batteries, and enveloping three sections of the armature, but electrically independent thereof. The batteries o' and o^2 are of different electro-motive forces, the battery o' having preferably about one-half as many cells as the battery o^2 , and they are so included in their respective circuits that currents of opposite polarities may be caused to traverse the corresponding solenoids, c' and c^2 , in the same or corresponding directions by closing their respective transmitting-keys K' and K^2 . Thus, when the key K' is closed, a positive current de-

rived from a battery having an electro-motive force of, say, ten volts will traverse the solenoid c' in the direction indicated by the arrow, and when the key K^2 is closed a negative current, derived from an electro-motive force of twenty volts, will traverse the solenoid c^2 in the same direction. The effect of the transmission of such currents will be to cause currents of proportionate strength to be generated 70 in the coils of the armature A, if it be revolved through or within the magnetic field thus created. When the key K' alone is closed, a series of impulses of alternating polarity will be generated in the coils a , having a strength 75 dependent upon the field of force occasioned by the passage of the current from the battery o' through the solenoid c' , and these impulses will be collected with respect to their polarity by the commutator-brushes b and b' 80 in a manner well understood. A continuous current or impulse of a given polarity—say positive—will thus be transmitted over the line L from the brush b , the duration of which will depend upon the duration of the current 85 traversing the solenoid. For convenience, this resultant current will be hereinafter referred to as due to an electro-motive force of ten volts. When the key K^2 alone is depressed, a current or impulse of a strength 90 dependent upon the field of force created by the flow of a current from the battery o^2 through the solenoid c^2 , but having the opposite polarity from that occasioned by closing the key K' , will be transmitted to the line. 95 This current may be considered as a negative current due to an electro-motive force of twenty volts. When both keys are simultaneously closed, the current sent to line will have a strength proportionate to the field of 100 force occasioned by the combined effects of the batteries o' and o^2 —that is to say, the current caused to traverse the main line will be a negative current due to an electro-motive force of ten volts. The current thus transmitted 105 may be considered a negative current. In this manner currents of three different strengths may be transmitted upon the main line through the instrumentality of the keys K' and K^2 , and these currents may be employed 110 for actuating two different receiving-instruments at station II, in a manner hereinafter described.

For the purpose of actuating a third receiving-instrument, I provide a third transmitting device, which consists of an electro-magnet, F, the armature of which consists of a tuned steel bar, f, constituting what is technically termed a "reed." This is rigidly secured at one end to a suitable support, while 115 the other end is free to vibrate under the intermittent attraction of the electro-magnet F. The bar or reed f can vibrate only at a determinate rate, depending upon its construction. It is provided with a contact-spring, g, which 120 is included, together with the electro-magnet F, in the circuit of the battery o^3 , which bat-

try is preferably of comparatively small electro-motive force—for example, three volts. This instrument constitutes an automatic interrupter, and when the circuit of the battery o^3 is closed by the depression of the transmitting-key K^3 the reed-armature will be thrown into vibration, the rate of which will depend upon the pitch or note to which it is tuned. 5 So long as the key K^3 remains depressed, this vibration will continue and the circuit of the battery o^3 will be broken at each vibration, thus establishing in the solenoid c^3 an intermittent or pulsatory current, the polarity and direction of which are preferably the same as 10 those of the current caused by the depression of the key K^2 to traverse the solenoid c^2 . The current generated in the coils a of the armature A , in response to the pulsatory currents in the solenoid c^3 , will, it is evident, itself be 15 pulsatory, and this current will be sent to line in the same manner as already described with reference to the keys K' and K^2 . When either or both keys K' and K^2 are depressed simultaneously with the key K^3 , the effect of the 20 pulsatory current will be to cause variations in the strength of the current transmitted upon the main line, without materially affecting its total strength. The effect, however, upon the receiving-instrument at station II, 25 corresponding to the key K^3 , will be the same as when that key alone is depressed.

Referring now to the receiving apparatus at station II, three instruments, $R' R^3 R^2$, are provided, which instruments are adapted to 30 respond, respectively, to the currents occasioned by the depression of the keys K' , K^2 , and K^3 , whether those keys be depressed one at a time or two or more simultaneously. To effect this result I provide the electro-magnet 35 m' of the receiving-instrument R' with a yielding contact-lever, r , which carries a stop against which the main armature-lever, r' , plays in lieu of the usual fixed stop. This contact-lever r is normally held by a spring, t , against 40 a fixed stop, s , and the local circuit of a battery, p' , which includes a sounder, S' , is made to traverse the armature-lever r' , the contact-lever r , and the fixed stop s . The retractile springs t and t' are so adjusted that when no 45 current traverses the electro-magnet m' both the armature-lever r' and the contact-lever r will fall against their back contact-stops. A current of either polarity having a strength 50 due to an electro-motive force of ten volts will be sufficient to cause the armature-lever r' to come in contact with the contact-lever r , but it will be insufficient to overcome the tension of the retractile springs t and t' and interrupt the local circuit by breaking 55 the circuit between the contact-lever r and the stop s . The sounder S' of the receiving-

instrument R' will therefore respond to those currents only which are transmitted while the key K' is depressed. The receiving-instrument R^3 , for responding to the movements of the key K^3 , consists of an electro-magnet, m^3 , provided with a polarized armature, r^3 , adapted to be thrown, under the influence of currents of negative polarity and due to an electro-motive force of ten volts or more, against a contact-stop, s^3 , thereby closing the circuit of a local battery, p^3 , and actuating the sounder S^3 . The receiving-instrument R^2 , adapted to respond to the rhythmical vibrations produced by the transmitter K^2 , consists of an electro-magnet, m^2 , provided with a reed-armature, r^2 , tuned to the same pitch as the transmitting-reed, and capable, therefore, of responding only to electrical vibrations or undulations having the same frequency or fundamental pitch as those occasioned by the transmitter K^2 . A local battery, p^2 , includes in its circuit a suitable instrument, S^2 , actuated by and in correspondence with the contacts of the reed r^2 with the contact-point s^2 , occasioned by the movements of the armature r^2 . In this manner I am enabled to transmit over one line, by means of three different transmitting devices at station I, currents of different characters which will be received and responded to by one, two, or three instruments 95 at station II.

For the purpose of transmitting messages simultaneously in opposite directions over the same wire, the apparatus above described may 100 be combined with any suitable system of duplexing of well-known construction.

In Fig. 2 I have illustrated a method of applying my invention to quadruplex telegraphy, which consists in employing one solenoid only 105 for creating the magnetic field for the armature A , and in organizing the transmitting apparatus either for varying the strength of the current which normally traverses the solenoid, or for reversing its polarity. The means 110 which I employ for this purpose consist of two transmitting-keys, K^4 and K^5 , one of which, K^4 , is a pole-changing key adapted to reverse the poles of the battery O , with reference to their connections with the terminals of the 115 solenoid c^4 , while the other key, K^5 , is arranged to throw in or out of circuit a portion of the main battery. For this purpose I prefer to construct the main battery O in two sections, o^4 and o^5 , the section o^4 having preferably an 120 electro-motive force of about five volts, while that of the section o^5 is ten volts. The key K^4 consists of an arm, k , constituting the key-lever and extending between two supplemental levers or arms, k' and k^2 , into electrical contact with either of which it may be brought. A resting contact-stop, s^4 , is provided common to both supplemental levers k' and k^2 , and against which one or the other rests when not in contact with the key-lever k . The resting contact s^4 is connected by a wire, 11, with one pole—in this instance the negative of the bat-

tery O—while the key-lever k^3 is connected by the wires 5 and 6 with the opposite pole of the same battery. The supplemental levers k^1 and k^2 are respectively connected with the terminals 9 and 10 of the solenoid c^4 .

The transmitting-key K^5 consists of a lever, k^3 , connected by the wire 6 with the positive pole of the battery-section o^5 , and provided with a supplemental lever, k^4 , connected by a wire, 8, with the positive pole of the battery-section o^4 . The supplemental lever k^4 normally rests upon a contact-point, O', through which the two battery-sections o^4 and o^5 are normally connected. When the key-lever k^3 is 15 pressed upward against the lever k^4 , the connection between the two battery-sections will be broken.

It will be understood from the foregoing that by operating the key K^5 the electro-motive force of the battery furnishing the current which normally traverses the solenoid c^4 will be reduced from fifteen to five volts, and by means of the key K^4 the polarity of the current traversing the solenoid, whether it proceed from both battery-sections or the section o^4 alone, may be reversed. The currents generated in the coils a of the armature A and transmitted to line will vary accordingly. Thus normally a current will be transmitted 30 upon the main line having a strength dependent upon the revolution of the armature at a given rate within the magnetic field created by a positive current proceeding from a battery having an electro-motive force of fifteen 35 volts and traversing the solenoid c^4 . If the key K^4 alone be depressed, the polarity of this current will be reversed, while its strength remains the same. If key K^5 alone be depressed, the current will be diminished in proportion 40 to the diminution in the strength of the solenoid-current, and if both keys K^4 and K^5 be simultaneously depressed the normal current upon the main line will be diminished to the same extent as when the key K^5 alone is depressed, and its polarity at the same time reversed. The currents of the three different 45 characters thus generated may be caused to actuate any suitable receiving-instruments at the distant station.

50 In the drawings I have shown two receiving-instruments, R^4 and R^5 , arranged to respond to the movements of the keys K^4 and K^5 , respectively. The instrument R^4 consists of an electro-magnet, m^4 , included in the circuit of the main line and provided with a polarized armature, r^4 , the magnetization of which is such as to cause it to respond to positive currents transmitted from the main line through the coil of its electro-magnet by striking 55 against the sounding-post q^4 in opposition to the force exerted by the retractile spring t^4 , but remaining inactive under the influence of a negative current.

60 The receiving-instrument R^5 consists of an electro-magnet, m^5 , likewise included in the circuit of the main line, but provided with a

neutral armature, r^5 , carried upon an armature-lever, q^5 . When resting against its back contact-stop, s^5 , the armature-lever q^5 closes the circuit of a local battery, p^5 , and actuates 70 a sounder, S^5 , in a manner well understood.

A retractile spring, t^5 , is adjusted to exert a sufficient tension upon the armature-lever q^5 to cause it to rest against its back contact-stop at other times than when it is attracted by a 75 current of greater strength than that generated in the armature A under the influence of an electro-motive force of five volts. The spring t^5 will, however, yield to the magnetism produced by a current of greater strength, and of 80 either polarity, traversing the coils of its electro-magnet, and bring the armature-lever q^5 against the front contact, thus breaking the local circuit.

The operation will be as follows: When both 85 keys are open, a negative current due to an electro-motive force of fifteen volts will traverse the line. The polarized armature r^4 will be held against the resting contact-stop t^4 , both by virtue of the retractile spring and the magnetism induced in the cores of its electro-magnet. The neutral armature r^5 , however, will be attracted with sufficient force to overcome the tension of the spring t^5 , and its lever will rest against its front contact, the sounder S^5 being 90 therefore inactive. If the key K^4 be depressed, a positive current due to an electro-motive force of fifteen volts will traverse the main line, and the polarized armature r^4 will respond accordingly. The reversal of the polarity of the 100 current will be too rapid, however, to allow the armature r^5 to fall away from its electro-magnet, and the sounder S^5 will still remain inactive. If the key K^5 alone be depressed, a negative current due to an electro-motive 105 force of five volts will traverse the main line. This current will produce in the electro-magnet m^4 magnetism of the polarity which tends to repel its armature r^4 from the sounding-post q^4 , and the receiving-instrument R^4 will 110 therefore remain inactive. The same current, however, will be insufficient to maintain the armature r^5 in its forward position in opposition to the force exerted by its retractile spring t^5 , and its lever will therefore fall 115 against the back contact, s^5 , and cause the sounder S^5 to be actuated. When both keys K^4 and K^5 are simultaneously depressed, a negative current due to an electro-motive 120 force of five volts traverses the main line and actuates the receiving-instrument R^4 , attracting its polarized armature r^4 against the post q^4 . The magnetism of the electro-magnet m^5 being insufficient to attract or to maintain its armature in its forward position, the sounder 125 S^5 will be actuated by the contact of the armature-lever q^5 with the back stop, s^5 , which thus closes the circuit of the battery p^5 .

The third method of applying my invention I have illustrated in Fig. 3, in which I have 130 represented a system of quadruplex telegraphy somewhat resembling that shown and de-

scribed with reference to Fig. 2. The plan, however, consists in employing a battery of constant electro-motive force, and throwing in or out of circuit a greater or less portion of the 5 solenoid surrounding the armature, instead of varying the electro-motive force of the battery.

In the drawings I have represented the armature A as surrounded by one solenoid, C, 10 composed of two sections, c^6 and c^7 . The two sections are normally connected with each other by means of a lever, k^7 , resting upon a contact-stop, s^7 . A battery, o^6 , having an electro-motive force of, say, fifteen volts, is 15 normally so connected with the terminals of the solenoid C that a positive current traverses the entire solenoid in the direction indicated by the arrow. Two transmitting-keys, K^6 and K^7 , are provided, the former of which 20 is of the same general construction as the key K^4 , described in connection with Fig. 2, and is arranged to reverse the poles of the battery o^6 with reference to its connections with the terminals of the solenoid by connecting the 25 positive pole of the battery through the wire 11 and key-lever k^6 with the supplemental lever k^8 or k^9 , according as the key K^6 is elevated or depressed, and thus by means of one of the wires 12 or 14 with one or the other terminal 30 of the solenoid C.

The key K^7 consists of a lever, k^5 , connected by a wire, 13, with the conductor 2, leading to one terminal of the solenoid C. When the key K^7 is depressed, it comes in contact with the lever k^7 , raising it from the contact-stop s^7 and closing the circuit of the battery o^6 through the wire 11, key-lever k^6 , and contact-spring k^8 , wires 12 and 13, key-lever k^5 , supplemental lever k^9 , solenoid-section c^6 , and wire 14 to 35 the contact-spring k^9 and stop S^6 , and by the wire 15 to the negative pole of the battery o^6 , thus cutting the solenoid-section c^7 out of circuit. Thus the key K^6 serves to reverse the polarity of the battery o^6 , while the key K^7 determines whether the entire solenoid or only 40 the section c^7 be included in circuit. Supposing the solenoid-sections c^6 and c^7 be so constituted that the induced current generated in the coils of the armature A by its revolution 45 through the magnetic field produced by the current from the battery o^6 traversing the solenoid-section c^6 has a strength one-third as great as that generated when the current traverses both sections c^6 and c^7 , then when 50 both keys are in their normal position the current transmitted to line may be considered as a positive current due to an electro-motive force of fifteen volts. When the key K^6 is depressed, it will be a negative current of the 55 same strength. When the key K^7 alone is depressed, it will be a positive current of one-third the normal strength, and when both keys K^6 and K^7 are simultaneously depressed it will be a negative current of one-third the 60 normal strength. In this manner, by operat-

ing the keys K^6 and K^7 individually and in combination, currents of the same character may be transmitted to the main line, as described with reference to Fig. 2, and these may be employed for actuating any suitable 70 receiving-instruments at the distant station, preferably, however, such as described in connection with Fig. 2.

It is obvious that any suitable and well-known system for transmitting and receiving 75 currents in opposite directions over the same line may be combined with the devices shown in Figs. 2 and 3, as well as with that shown in Fig. 1.

I am aware that it is not new to employ induced currents for actuating the receiving-instruments of a telegraphic system, as it has been proposed to locate a magneto-electric generator at the receiving-station of such a system, and to include the coils of its field-magnets in the circuit of the main line, the receiving-instruments in such case being included in a local circuit with the armature of the generator. In such an organization, however, the transmitting-instruments must be 80 located in the circuit of the main line, and the incoming impulses are thus compelled to pass through the same, whereas in my organization such currents are provided with an earth-connection which is independent of the transmitting-instruments, and is, moreover, of practically 85 constant resistance.

I claim as my invention—

1. The combination, substantially as hereinbefore set forth, with the armature of an 100 electric generator and one or more solenoids for establishing a field of force for said armature, of one or more exciting generators, independent devices for transmitting at will 105 electric currents, impulses, or undulations from said exciting generator or generators through the conductor or conductors constituting said solenoid or solenoids, a main line, and connections, substantially such as described, for transmitting electric currents from 110 the coils of said armature upon said main line.

2. The combination, substantially as hereinbefore set forth, with the armature of an 115 electric generator, of a main line, means for maintaining the terminals of said main line in electric connection with the coils of said armature, one or more solenoids for establishing a field of force for said armature, one or 120 more local electric generators, and means for transmitting at will determinate electric currents, impulses, or undulations through any or all of said solenoids.

3. The combination, substantially as hereinbefore set forth, with the armature of an 125 electric generator, its commutator and commutator-brushes, and means, substantially such as described, for establishing or varying the field of force of said armature, of an independent main line connected with the earth 130

through said commutator and commutator-brushes, and one or more telegraphic receiving-instruments included in said main line.

4. The combination, substantially as hereinbefore set forth, with the armature of an electric generator, its commutator and commutator-brushes, and transmitting devices for controlling the field of force created by electric currents traversing the solenoids of said generator, of an independent main line connected

with the earth through said commutator-brushes, and receiving-instruments included in said main line.

In testimony whereof I have hereunto subscribed my name this 24th day of August, A. D. 1882.

STEPHEN D. FIELD.
